Application March 8, 1954, Serial No. 29,398

Term of patent 3½ years

(Cl. D48—20)

To all whom it may concern:

Be it known that I, Arthur F. Jacobs, a citizen of the United States, residing in Los Angeles, county of Los Angeles and State of California, have invented a new, original, and ornamental Design for a Height-Adjustable Floor Lamp, of which the following is a specification, reference being had to the accompanying drawing, forming part thereof.

Fig. 1 is a perspective view of a height-adjustable floor lamp, showing my new design.

Fig. 2 is a perspective view thereof to a smaller scale, showing the lamp in another position.

The dominant features of the design are shown in full lines in the drawing.

I claim:

The ornamental design for a height-adjustable floor lamp, substantially as shown and described.
